UNITED STATES PATENT OFFICE.

ERIC GUSTAF KINBERG, OF NEW YORK, N. Y.

COVER FOR JOURNAL-BOXES.

No. 853,460.

Specification of Letters Patent.

Patented May 14, 1907.

Application filed July 27, 1906. Serial No. 328,021.

To all whom it may concern:

Be it known that I, ERIC GUSTAF KINBERG, a subject of the King of Sweden, residing at New York city, in the county and State of New York, have invented certain new and useful Improvements in Covers for Journal-Boxes, of which the following is a full, clear, and exact specification, reference being had to the accompanying drawings, and to the reference characters marked thereon.

This invention has relation to covers for journal boxes, particularly such covers as are employed in connection with journal boxes for railway cars to close the opening through which the packing and lubricating material are supplied to the box and journal, although the improved form of cover may be advantageously employed in connection with other forms of journal boxes wherever situated.

The object of my invention is to provide a simple, cheap, efficient and reliable cover for journal boxes which will be automatically held in perfect contact with the margin of the opening which it is intended to close, which may be easily opened and automatically held in open position for the purpose of gaining access to the interior of the journal box, and which may be easily applied and removed whenever desirable or necessary.

To accomplish all of the foregoing object and to secure other and further advantages in the matters of construction, operation, application and use, my improvements involve certain new and useful relative arrangements or combinations of parts, peculiarities of construction and principles of operation, all of which will be herein first fully described and then pointed out in the claims.

In the accompanying drawings forming part of this specification, I have shown my improved form of cover as applied upon one of the ordinary forms of car axle journal boxes for the purpose of illustrating my invention and the principles on which it operates.

Figure 1 is a sectional elevation on a plane through the longitudinal axis of the box showing the cover in full lines in closed position and in dotted lines in other positions. Fig. 2 is a front elevation of the box and cover corresponding with Fig. 1. Fig. 3 is an elevation of the spring actuating

plunger disconnected from its position in 55 the spring socket on the cover and from its bearing on the journal box.

In all these figures like letters of reference, wherever they occur, indicate corresponding parts.

A represents a car axle journal box which may be of any approved form or construction and which stands in the place of any other journal box in connection with which my improvements may be advantageously 65 employed in accordance with the purposes of my invention.

B is a cover for the front opening in the journal box, this being arranged, as are covers of other forms, to close the front opening in 70 the journal box through which access is to be had from the exterior to the interior. The seats for these journal box covers are ordinarily made plain and slightly inclined, and the covers are ordinarily intended 75 to fit upon or against these seats to exclude dust and other matters from the exterior; but these covers being usually hinged so as to turn upon stationary axes or hinge pins, materials accidentally lodged upon the seat 80 effectually preclude close contact of the covers with the seats and therefore permit the passage of fine dust or grit into the interior of the box, which is detrimental and should be avoided.

Various means have been proposed for locking the ordinary forms of journal box covers in closed position, but these are liable to become loosened or disarranged and the cover thereby left to swing open, affording 90 opportunity for dust and dirt to enter the box from the exterior.

To obviate the objections above referred to, I mount the cover so that it will swing in the desired directions but not around a stationary axis; and I supply the cover with a spring and means for operating the same to keep the cover constantly pressed against its seat or to hold it in open position according to the position to which it is adjusted.

C is a socket formed on the exterior of the cover or otherwise applied in connection therewith, the socket being preferably closed except for the opening at the top to receive the spring actuated plunger, and being arranged parallel with the face of the cover. The lower portion of this socket forms a convenient part for the bearing of the yoke by

which the cover is sustained and connected with the upper part of the journal box. D represents this yoke, the same being continuous and reaching from the lower part of the 5 spring socket, around the same and around a projection, a, on the top of the box. This yoke is slightly bent at its upper part, as indicated, to afford the desired movements of the cover and the desired action of the 10 spring in connection therewith and to accommodate itself to different positions of the parts without interference.

The coiled spring within the socket is represented at E, and this is made sufficiently 15 powerful to afford the requisite pressure on the cover. Upon the top of the spring is a plunger F, the same being preferably supplied with a neck, b, to enter the upper part of the coil of the spring and an enlargement, 20 c, to properly fit the interior of the spring socket to exclude dust and dirt therefrom and to bear upon the top of the spring, and is provided with a head, d, extending upon both sides of the axis of the plunger, the 25 head being arranged to bear in a recess formed in the front of the projection a on the journal box. The bearing for the yoke on the bottom of the socket and that for the plunger against the projection a are each 30 sufficiently recessed to prevent accidental disengagement of the parts after they have been properly assembled; and the bearing for the yoke on the cover is located at about the middle of the cover. The front of the projection a is recessed, as at d', to accommodate 35 the shank of the plunger when the cover is swung up to its limit or fully opened position. The limit of the swing of the cover in an upward direction is determined by a short lug, 40 f, formed on the yoke, this lug striking against the top of the box when the cover is swung up to its limit.

At g is a simple form of finger piece applied upon the lower part of the cover to facilitate 45 opening it when necessary, but this may be replaced by any other suitable projection.

The cover, with its appliances thus constructed and arranged, is mounted in place 50 by simply hooking the top of the yoke back of the projection a and then forcing the head of the plunger down over the front of the projection. This movement will compress the spring sufficiently to enable the head of the 55 plunger to enter the recess provided for it in the projection. Being so applied, the spring presses always in the direction of the longitudinal axis of the socket, and this being inclined, or forming an angle with respect to the center plane of the yoke (the plane through the upper and lower parts of the yoke) one component of the force acts in a 60 direction perpendicular to the face of the cover and therefore holds the cover always 65 against its seat so long as the spring pressure

is not overcome. As before indicated, the spring is made of ample strength for the purposes intended, and it should hold the cover in closed position against any possibility of disarrangement by jolting or jarring or other 70 ordinary use to which it may be subjected.

When the cover is swung open, as it may be by application of the hand to its lower part, it does not swing on a stationary axis as on an ordinary hinge pin but moves in 75 the yoke as constrained by the pressure of the plunger against the projection on the top of the box, and thus it turns about a variable or movable axis. In swinging from the closed position to the intermediate position 80 indicated by dotted lines in Fig. 1, wherein the bottom of the yoke, the head of the plunger and the top of the yoke are in the same straight line, the tendency of the spring to close the door becomes less and less powerful 85 until the cover reaches this neutral or intermediate position, where the tendency to close it is zero. Passing by this intermediate position, the tendency of the spring is to further swing the cover in the direction of the opening 90 movement. Reaching the uppermost position, indicated by the dotted lines in Fig. 1, the cover is held fully opened by one component of the force of the spring (then acting in a direction opposite that previously referred to) so that the interior of the box may be easily reached. To again close the cover, it has only to be forced downward until it swings past the intermediate position, when 95 it will automatically close under the action 100 of the spring. The limit of the upward swing of the cover is determined by the lug f striking against the box, as before indicated. The power required to lift the cover from the closed to the neutral position constantly 105 diminishes as the cover swings, which renders it easy to open the cover. To detach the cover, it is only necessary to force its outer margin up sufficiently so that the head of the plunger will ride out of the recess provided 110 for it in the top of the box.

From the foregoing explanations it will be understood that the cover is firmly and accurately seated at all times when down and that it approaches its seat by a movement 115 substantially parallel thereto rather than by a movement around a fixed axis, being freely movable upon the supporting part of the yoke, so that any obstruction at one point to its perfect seating will not interfere with its 120 perfect seating at other points; and the spring acting at the middle part of the cover which is movable with respect to the sustaining yoke, forces the cover to its seat with power equal at all points of contact. 125

Being constructed and arranged substantially in accordance with the foregoing explanations, the improvements will be found to admirably answer all the purposes or objects of the invention hereinbefore alluded to. 130

Having now fully described my invention, what I claim as new herein and desire to secure by Letters Patent, is:—

1. The combination with a journal box, of a cover therefor, a removable yoke for connecting the cover and box, said cover being engaged with the yoke at about the middle part of the cover and arranged to swing upon and with the yoke, and a spring and coöperating plunger for automatically holding the cover both in closed position and in opened position, substantially as and for the purposes set forth.

2. In combination with a journal box, a cover therefor, a spring parallel with the plane of the cover, a plunger operating in connection with the spring, and a removable swinging yoke for connecting the cover with

the box, substantially as and for the purposes set forth.

3. The combination, of a journal box, a cover therefor having a socket thereon parallel with the face thereof, a spring located in the socket, a plunger, and a removable yoke connecting the cover at about its middle part with the journal box, said yoke being supplied with a projecting lug at its upper part, for the purposes set forth.

In testimony whereof, I have signed my name to this specification in the presence of two subscribing witnesses.

ERIC GUSTAF KINBERG.
